Application September 21, 1939, Serial No. 295,947

10 Claims. (Cl. 46—107)

This invention relates to action toys, and has for one of its objects the provision of a simple and rugged toy embodying a novel and improved form of toy figure movement. Other objects and 5 advantages of the invention will appear from the specification herein.

In the drawings:

Fig. 1 is a fragmentary side elevation of a toy embodying the invention;

10 Fig. 2 is a top plan view of the toy of Fig. 1 showing portions of the actuating mechanism thereof;

Fig. 3 is a perspective of a portion of the actuating mechanism of the toy of Figs. 1 and 2;

15 Fig. 4 is a diagrammatic illustration of a movement of another form of the toy of Figs. 1 to 3;

Fig. 5 is a side elevation of another form of toy of the invention, showing the moving elements thereof in different positions; and

20 Fig. 6 is a front elevation of a portion of the mechanism of Fig. 5.

As illustrated in Figs. 1, 2 and 3, the toy comprises a baseboard 10 mounted upon traction wheels 12 by means of a transverse axle 14 and suitable bearings (not shown). The axle 14 25 is of crank form as at 15, and engages therewith the looped lower ends of links 20 for imparting movement to toy figure limb elements. The upper ends of the links 20 are pivotally 30 connected as at 21 to limb elements 22 which are pivotally mounted as by means of pins 23 at positions offset from the pivotal connections 21 upon a toy figure body portion 24 which is fixed to the base plate.

35 Lower limb elements 28 are connected in articulated manner to the oscillatable end portions of the upper elements 22 as by means of pivot pins 30. At positions spaced from the pivot pins 30 the lower limb elements are provided 40 with guide devices in the form of laterally extending staples 32 which are arranged to embrace the link member 20 corresponding thereto in longitudinally slidable relation. Thus, upon rotation of the wheels 12 the links 20 cause the 45 upper limbs 22 to oscillate about the pivot pins 23 and this causes the upper ends of the lower limbs 28 to move with the outer ends of the upper limbs in such manner as to simulate the movements of the knees of a cycle rider.

50 The guide devices 32 provide a special type of fore and aft movement of the lower ends of the limbs 28 without interfering with vertical movement thereof as produced by the alternate lifting and falling of the outer ends of the limbs 55 22. It will be seen that as the links 20 move in

response to the crank action of the axle the components of the crank motion in fore and aft directions are transmitted to the intermediate portion of the links 20 in the region of the guides 32 to a predetermined lessened extent, 5 and thus the lower ends of the limbs 28 are given components of motion in fore and aft directions to such degree as to combine with the vertical motions thereof to produce a circular type of motion as viewed in side elevation.

10 It will be seen that the ratio of the vertical to transverse motions in fore and aft directions may be regulated as desired by varying the proportioning of the actuating elements.

For example, as illustrated in Fig. 4 and as 15 distinguished from the arrangement of Figs. 1 and 3, the point of pivotal connection 21 may be located closer to the pivot pin 23 to decrease the amplitude of oscillation of the outer end of the limb 22, thus making the extent of vertical movement of the lower end of the limb 28 20 more nearly equal to the extent of the fore and aft movement thereof; and it will thus be understood that there is available a wide range throughout 25 which the connection point 21 may be shifted 30 relative to the pivot pins 23 and 30 whereby any desired type of curvilinear foot path may be obtained. More specifically, Fig. 4 illustrates the connection point 21 as being coincident with the pivot pin 30; and the elliptical path of motion of a point on a foot portion of the lower limb 28 is illustrated thereon by a broken line at 35. In such case the link 20 could be conveniently looped at its upper end about the pivot pin 30 which would then function simultaneously 35 as a connection device between the link 20 and the upper limb 22 and between the upper limb 22 and the lower limb 28.

40 It will be understood that variations in the type of foot motion produced may be affected by altering the throw of the crank portions 15 of the axle and/or by changing the distance between the staple 32 and the crank. It will also be understood that in lieu of the crank shaped axle 14, any other suitable form of motion imparting device may be employed; such as for example, direct pivotal connection of the lower ends of the links 20 to pins extending laterally from the traction wheels at points eccentric of the axis of rotation thereof.

45 Thus the foot portions of the limbs 28 are made to appear to move in paths resembling typical peddling motions, and the most prominently displayed elements of the toy are moved in realistic and novel fashion by means of a sim- 50

ple and rugged structural arrangement. The crank portions of the axle 14 are illustrated herein as being opposed to one another, and hence the knees of the toy figure of the drawing will move in opposite directions or in out-of-phase relation at all times; but it will be understood that the principle of the mechanism may be applied to other types of toy figure designs having one or more systems of movable elements 10 and at any desired relationship with respect to other movable elements of such toys.

Fig. 5 illustrates another form of the invention wherein an upper limb 40 is provided in a manner corresponding generally to the limb 22 15 of Figs. 1 and 3; and is arranged to be oscillated about a point of pivotal connection 42 by means of a link 44 connecting with a crank portion of the traction wheel axle. A lower limb member 46 is articulated to the limb 40 by means of a pin 48, and the outer end of the limb 46 is arranged to be guided in its motion by means of a staple 50 and a rod 52 which extends between 20 and is pivotally connected to the pivot pin 48 and a supporting bar 56. The bar 56 is pivotally mounted upon the toy frame as at 58.

Thus, upon rolling the toy across a floor or other supporting surface, the traction wheel 12 oscillates the link 44 vertically through means of the crank arrangement and causes the limb 40 to 30 oscillate about the pivot pin 42. This motion in turn causes the limb 46 to move with a compound motion, the inner end of the limb following the arc of movement of the pivot pin 48 and the other end of the limb 46 being guided by means of 35 the rod 52 in a substantially straight line path of motion. Thus the limb 40 corresponds to the limb 22 of Fig. 1 and the rod 52 corresponds to the limb 28, and a type of motion similar to that provided for in connection with Figs. 1 to 3 is arranged, but it will be noted that the action of Fig. 40 5 simulates in realistic fashion the elbow action of an animated arm as in connection with the ringing of a locomotive bell 60, or the like. As illustrated in Figs. 5 and 6, the bar 56 may be 45 provided of wire bent into an inverted U shape and provided at its center cross arm portion with an inwardly bent U portion 62 adapted to extend through an opening in the top portion of the bell 60, formed by striking out portions 64 thereof. 50 Prior to assembly of the bell 60 upon the bar 56 a bell striker 65 in the form of a metal bar provided with an opening therethrough at its upper end is threaded upon the bar 56 in such manner as to be suspended from the U-shaped portion 62 55 in freely rotatable relation thereon. The struck out portions 64 are then hammered down into clamping relation upon the bar 56, and the bell 60 is thus gripped upon the bar in such manner as to be rigid thereon whereby reciprocation of the bar 52 will cause the striker 65 to oscillate and 60 contact the bell wall for the production of musical notes.

Attention is called to the novel formation of the link members 20 at their upper ends in the 65 region of their pivotal connections with the limbs 22. As illustrated in Figs. 2 and 3, the links 20 are reversely bent adjacent the finger portions 21 thereof so as to extend the portions 21 in each case laterally beyond the line of the link 20 toward the body portion 24 of the toy. Thus, guide means are provided for maintaining the link 20 in spaced relation from the body 24 and for maintaining the finger portion 21 in pivotal engagement with the limb 22.

Although the invention has only been described

and shown by way of example herein, it will be understood that various changes may be made therein without departing from the spirit of the invention or from the scope of the appended claims.

5

I claim:

1. In an action toy, a traction wheel, a toy figure, a limb-simulating member pivotally mounted upon said toy figure, a connecting rod associated with said traction wheel and said limb member in such manner as to procure oscillation of the latter upon rotation of said traction wheel, a second limb member articulated to said first limb member and disposed adjacent said connecting rod, and a pair of abutments extending from said second limb member at a position spaced from the point of articulated connection and embracing said connecting rod at opposite sides thereof in such manner as to coordinate the vertical components of movement of the outer end of said second limb member and the components of its movement laterally thereof in a predetermined manner.

2. In an action toy, a traction wheel, a toy figure, a limb-simulating member pivotally mounted upon said toy figure, a connecting rod associated with said traction wheel and said limb member in such manner as to procure oscillation of the latter upon rotation of said traction wheel, a second limb member articulated to said first limb member and having a portion extending therefrom, a guide member extending from said extending end portion of said second limb member, and a guide rod pivotally mounted at one of its ends at said point of articulated connection and mounted at the other of its ends upon said toy figure in longitudinally movable relation and slidably associated intermediately of its ends with said guide means in such manner as to maintain the extending end portion of said second limb member in a substantially straight line of motion upon rotation of said traction wheel.

3. In an action toy, a bell frame comprising a bent wire having an upright portion pivotally mounted at its lower end upon said frame and a laterally bent portion at its upper end, said laterally bent portion being bent intermediately thereof so as to form a U shaped projection thereon, a bell striker journaled upon said projection portion, and a bell having a top wall portion struck out to provide an opening therethrough into which said projection portion is inserted, said struck out portion being bent in such manner as to clamp said bell frame lateral portion against the top wall of said bell in rigidly mounted relation thereon.

4. In an action toy, a traction wheel, a toy figure, a limb simulating member pivotally mounted upon said toy figure, a connecting rod associated with said traction wheel and said limb member in such a manner as to procure oscillation of the latter upon rotation of said traction wheel, a second limb member articulated to said first mentioned limb member, and guide means associated with said second limb member adapted to maintain the outer end portion of said second limb member in a substantially straight line path of movement during operation of said toy.

5. In an action toy, a traction wheel having a laterally extending crank, a toy figure, a limb-simulating member pivotally mounted upon said toy figure, a link connecting said crank and said limb-simulating member at a position offset from the point of its pivotal mounting, a second limb member articulated to said first mentioned limb

75

member, and guide means associated with said second mentioned limb member at a position spaced from the point of said articulated connection, said guide means being adapted to maintain 5 the adjacent portion of said second mentioned limb member in a substantially straight line path of movement upon operation of said toy.

6. In an action toy, a traction wheel having a laterally extending crank portion, a toy figure, a movable member pivotally mounted at one of its ends upon said toy figure, a link connected at its opposite ends to said crank portion and to said movable member at a position spaced from the point of said pivotal mounting and laterally 10 offset with respect to the line between said pivotal connection and said crank portion, a second movable member articulated to said first movable member and extending from the point of said articulated connection toward said crank portion, 15 and slide guide means mounted upon an extending end portion of said second movable member and associated with said link at a position intermediate of its ends, whereby a predetermined composition of oscillative movements in transverse directions is imposed upon the extending end portion of said second movable member.

7. In an action toy, a body member, a movable member mounted upon said body member and in spaced relation therefrom, a link member disposed within the space between said body member and said movable member and operatively associated with said movable member for actuating the latter to different positions relative to said body member, said link member having a laterally 30 offset portion extending into pivotal engagement with said movable member and a laterally offset portion extending into sliding engagement with said body member for guiding said link member relative to said body member and maintaining 35 said link member in operative engagement with said movable member.

8. In an action toy, a traction wheel provided with a laterally extending crank portion, a toy figure, a movable member pivotally mounted upon 40 said toy figure, a connecting rod associated with said crank portion and said movable member in such manner as to procure oscillation of the lat-

ter about the point of said pivotal connection upon rotation of said traction wheel, a second movable member articulated to said first mentioned movable member and having a portion extending beyond the point of said articulated connection, and a closed yoke member mounted upon said extending portion of said second movable member and extending laterally thereof and into sliding engagement with said connecting rod, said extending end portion of said second movable member being slidably guided by said yoke member longitudinally of said connecting rod upon operation of said toy.

9. In an action toy, a traction wheel unit, a toy figure, a pair of limb simulating members pivotally mounted upon opposite sides of said toy figure, connecting rod means associated with said traction wheel unit and said limb members in such manner as to procure synchronized opposite oscillative movements of said limb members upon 20 actuation of said traction wheel unit, second limb members articulated to each of said first mentioned limb members, and guide means mounted upon and extending from said second limb members and loosely embracing elements of said connecting rod means for maintaining the outer end portions of said limb members in substantially straight line paths of movement during operation of said toy.

10. In an action toy, a traction wheel unit, a toy figure, a plurality of limb simulating members pivotally mounted upon said toy figure, connecting rod means associated with said traction wheel unit and said limb members in such manner as to procure synchronized out-of-phase oscillative movements of said limb members upon actuation of said traction wheel unit, second limb members articulated to each of said first mentioned limb members, and guide means associated with each of said second limb members and loosely embracing elements of said connecting rod means for maintaining the outer end portions of said second limb members in substantially straight line paths of movement during operation of said toy.

HERMAN G. FISHER.
